UNITED STATES PATENT OFFICE.

REUEL W. WARE, OF PORT JERVIS, NEW YORK.

IMPROVEMENT IN VEHICLE-SPRINGS.

Specification forming part of Letters Patent No. **157,656**, dated December 8, 1874; application filed January 31, 1874.

To all whom it may concern:

Be it known that I, REUEL WILLARD WARE, of Port Jervis, in the county of Orange and State of New York, have invented a certain new and useful Improvement in Carriage-Springs, of which the following is a specification:

It is the object of my invention to produce a carriage-spring of nearly uniform elasticity, whether under a light or under a heavy load; to combine the spring and reach or coupling-rod so as to work together and assist each other in sustaining the load, strengthen and add elasticity to the spring, hold it in check, and prevent a sudden reaction or flying upward immediately after a plunge or depression; to dispense with unnecessary weight, and to cheapen the cost of construction.

The subject-matter claimed will be herein-after specified.

In the accompanying drawings, Figure 1 is a side elevation of my improved spring, and Fig. 2 a similar view of a modified form of the same.

A yielding or elastic coupling-rod or reach, A, preferably of wood, but which may be of steel or other metal, or metal and wood combined, is connected to the rear axle and front bolster of the vehicle by means of bolts, clips, or other suitable fastenings, with such additional brace-rods or angle-ties between the bolsters or axles and the reach as may be desired, or are necessary to produce lateral stability. The reach has a camber or stands crowning, in which position it is sustained by a steel spring, B, attached at its ends to the reach by links or ties C, or in any other equivalent manner, admitting of a backward and forward or oscillating movement of the spring as it elongates and contracts when working under a load. A seat or body bolster or rocker, D, is fastened to this combination spring, composed of the reach or coupling and the steel spring, by bolts or other suitable means. A spreading-block, F, is, by preference, secured between the reach and spring, although, if desired, it may be omitted without materially affecting the operation of the spring.

Two or more springs, each composed of the

parts A and B, are intended to be used together, placed parallel, and extending from the front bolster or rocker to the rear axle, as described.

The piece of which the reach is composed and the steel spring are so adjusted each to the other that when applied to the carriage the piece or reach is curved or cambering, as shown, and is held in this position by the upward pressure of the spring B upon the block E, (or by pressure at the point of contact of the spring at its center with the reach, should the block be dispensed with,) until the load of the carriage becomes equal to or greater than the pressure of the spring B, when the strip A is restored to a level position, or assumes a deflected position below a level line, and relieves the spring of so much of the weight of the load as is necessary to straighten or deflect the strip.

It is obvious that the reach may be so formed that its camber is independent of or not formed by the pressure of the spring, in which case the result would be the same.

In Fig. 2 I have shown the steel spring upon the top of the reach, the ends of the spring resting on the reach, by which construction the ties or shackles C are dispensed with, while the operation is essentially the same.

By my construction a cheap, light spring is produced.

By the joint action of the spring and reach injurious shocks and jars are, in a great measure, avoided, and by means of the movable points of support of the spring it is also relieved of the severe strain to which carriage-springs are usually subjected when suddenly depressed under heavy loads.

I claim as my invention—

The combination of a yielding reach and a spring centrally connected therewith, and having its ends capable of moving endwise on the reach, as set forth.

In testimony whereof I have hereunto subscribed my name.

REUEL WILLARD WARE.
